UNITED STATES PATENT OFFICE.

MAURICE BLUMENTHAL, OF BROOKLYN, NEW YORK.

MEANS FOR AND METHOD OF PRODUCING CONCRETE PILES.

Application filed August 5, 1919. Serial No. 315,461.

To all whom it may concern:

Be it known that I, MAURICE BLUMENTHAL, residing at Brooklyn, in the county of Kings and State of New York, have invented 5 certain new and useful Improvements in Means for and Methods of Producing Concrete Piles, of which the following is a specification.

This invention relates to a means for and 10 method of producing concrete piles in the earth, the present application being a companion to my pending application Serial No. 315,460.

An object of the invention is to provide 15 a pile having extensive projections laterally thereon, said projections, or arms, being extended into the surrounding earth so as to provide additional bearing surface of the pile against the earth to thereby increase 20 the efficiency of the pile in sustaining such weights as may be applied to the upper end of the pile.

A further object is to provide a pile in 25 which the extensions, or arms, are formed of the concrete material of the pile and in which the extensions are provided with metallic reinforcing means extending into the body of the pile.

A further object is to provide a pile having 30 the above characteristics and in which no shell or container of any kind is necessarily allowed to remain in the earth after the pile is completed.

A further object is to provide a simple 35 and efficient method whereby to insure the formation of the lateral arms upon the pile.

A further object is to provide a method 40 in which the reinforcing elements for the lateral arms are themselves made use of in the formation of pockets within the earth, which pockets are adapted to receive the concrete material for the arms.

Other objects and aims of the invention, 45 more or less specific than those referred to above, will be in part obvious and in part pointed out in the course of the following description of the elements, combinations, arrangements of parts and applications of principles, constituting the invention; and 50 the scope of protection contemplated will be indicated in the appended claims.

In the accompanying drawings which are 55 to be taken as a part of this specification, and in which I have shown merely a preferred form of embodiment of the invention;

Fig. 1 is a longitudinal sectional view illustrating the first step in the course of constructing a pile in accordance with this invention. 60

Figs. 2 and 3 are views similar to that shown in Fig. 1, but illustrating successive further steps in the work of forming the pile.

Fig. 4 is a side elevational view of a completed pile. 65

Fig. 5 is a view similar to that shown in Fig. 4 but illustrating a modification, and

Fig. 6 is a top plan view of a modified 70 form of the arm-forming and reinforcing element.

While the drawings herein illustrate the pile former, or shell, as being of the non-sectional type, yet it will, of course, be understood that a sectional shell may be 75 employed in many instances and that the objects of this invention may be attained equally well with either type of shell.

Referring to the drawings, and particularly to the structure shown in Figs. 1 to 4; 80 for describing in detail the features therein illustrated, the reference character L indicates a pile former or shell, and the reference character G indicates a nose piece positioned at the lower end of the shell for facilitating the driving of the shell into the earth. 85

After the shell L, with its nose piece G, has been driven into the earth, as indicated in Fig. 1, and before the pouring in 90 of the concrete, the shell is lifted a slight distance, as indicated in Fig. 2. With the shell in this position one of the arm forming and reinforcing elements, as H, is lowered into the shell and into engagement with a 95 guide plate 1 previously lowered. In some instances it may be desirable to place the guide plate and the former H within the shell before the shell is raised.

A driving weight 2 is then lowered into 100 the shell and is employed for driving the former H downwardly and outwardly into the earth below the lower edge of the lifted shell, the former H at different periods occupying the successive positions indicated 105 by the dotted lines in Fig. 2.

The former H may be of any appropriate construction, its essential characteristics being simply that blows, or other appropriate operation thereupon will cause portions of the former to be forced outwardly 110 into the surrounding earth, the operation

preferably serving to scoop out pockets, as 3, within the earth communicating with the interior of the shell.

In the instance illustrated, the former 5 consists simply of two members, as 4 and 5, pivotally connected together, as at 6. The members 4 and 5 are of U-shape cross section, each providing a top wall 7 having opposite side flanges 8 thereon. The blows 10 from the weight 2 are applied at the pivot 6 and the lower ends of the members 4 and 5 are thus caused to slide or cam over the opposite edges of the guide plate 1, the top walls 7 of said members then serving to scoop out 15 and press back the earthy material so that when the members 4 and 5 are in their final positions, as seen in Fig. 3, they will constitute roof portions for the pockets 3 which have been formed by their movement. The 20 flanges 8 serve to hold the top walls lifted away from the guide plate so as to form suitably proportioned passages 9 communicating between the pockets 3 and the interior of the shell.

25 The former is allowed to remain in this position, the weight 2 is withdrawn and a quantity of concrete material of suitable consistency is introduced into the shell and is allowed to flow outwardly thru the passages 9 into the pockets 3 filling said pockets and passages. More of the concrete material is then introduced. The lifting of the shell and the pouring in of more concrete material may then progress until the pile is 35 completed without introducing more of the formers H.

The concrete material which has flowed into the pockets 3 forms the arms 10 and is integral with the concrete material of the 40 main body of the pile. The members 4 and 5 of the former H comprise portions of said arms and effectually reinforce the arms since they extend from connected relation within the body outwardly over the upper 45 surfaces of the concrete material of the arms.

Wherever it is desired to provide more of the arms 10 this may be readily accomplished by simply introducing additional 50 guide plates 1 and formers H at different levels as the filling in of the concrete material of the pile progresses, as is clearly indicated by the illustration Fig. 3. The operation in each instance will be the same 55 as has already been described for the lowermost arms.

In this way the piles, having a multiplicity of arms, such as are illustrated in Figs. 4 and 5, may be formed.

60 The nose piece G is allowed to remain in the earth and serves as a suitable foundation directly beneath the main body of the pile after the pile is completed.

In the illustration Fig. 5 the construction 65 and mode of operation for producing the

pile of this figure is substantially the same as has already been described except that in this figure is illustrated a separate auxiliary shell, or container 11 for the concrete material, which auxiliary shell is allowed 70 to remain in the earth after the main shell L is removed. The shell 11 may be of thin sheet metal, or it may be of any other appropriate material, such as paper or the like, as indicated in my pending application Serial No. 306,134, and it may be introduced into position either after the main shell L is sunk into the earth or it may be placed around the outer surface of the shell L and sunk into the earth therewith, as may 75 be found most appropriate and convenient.

Where the auxiliary shell 11 is present the formers H simply tear thru the material thereof in the process of forming pockets 3 for the arms 10.

The presence of the auxiliary shell may be of importance in some cases, for instance, where the surrounding earth is of a soft or unstable character. In these cases the auxiliary shell will serve to maintain the main 90 body of the pile in proper pile formation during the setting period.

Also, where the auxiliary shell is closed at its bottom end, or is otherwise waterproof, as suggested in the co-pending application 95 referred to, said shell will serve to prevent the ingress of soft earth or of water thereinto during the sinking of the shell L into the earth and prior to the introduction of the formers H.

In the modification Fig. 6 an arm-forming element is indicated which consists of four separate formers or reinforcing members 12 all pivotally connected to a single central member 13. This type of former may be employed in some instances where the earth is suitably soft and where it is desired to provide greater bearing surface upon the earth.

As many changes could be made in this 110 construction, without departing from the scope of the following claims, it is intended that all matter contained in the above description, or shown in the accompanying drawings, shall be interpreted as illustrative only and not in a limiting sense.

Having thus described my invention, what I claim as new and desire to secure by Letters Patent is:

1. A concrete pile comprising a body of 120 concrete material in pile formation, an integral arm of the concrete material projecting laterally from said body, and a reinforcing member for said arm engaging the upper surface thereof and projecting into 125 embedded relation within the body.

2. A concrete pile comprising a body of concrete material in pile formation, a plurality of integral arms of the concrete material projecting laterally from said 130

- body at substantially diametrically opposite points, and reinforcing means for said arms extending therefrom transversely thru the body.
- 5 3. In a concrete pile construction, means for forming a pile-shaped opening within the earth adapted to receive concrete therein, and a former by which to form a pocket within the earth in the wall of said opening 10 communicating with the interior of the opening adapted to receive a portion of the concrete subsequently placed within said opening, said former being intended to remain in position after the placing of the 15 concrete and comprising parts adapted to extend between the pocket and the pile-shaped opening so as to reinforce the connection between the concrete within said pocket and the concrete within said opening.
- 20 4. The herein described method of forming a concrete pile which consists in providing a shell, sinking said shell into the earth, introducing a pocket forming element into the shell, lifting the shell for a short 25 distance, thereafter forcing said pocket forming element outwardly beneath the lower edge of the shell into the surrounding earth for forming a pocket in the earth communicating with the opening left by the 30 lifting of the shell, and then filling said pocket with concrete material extending into the opening beneath the shell.
5. The herein described method of forming a concrete pile having a plurality of 35 lateral arms formed thereon at different points in the length of the pile, which consists in forming a pile-shaped opening within the earth, forming a pocket in the wall of said opening, placing a quantity of concrete material within said opening to fill the 40 pocket and to partly fill the opening, utilizing the top portion of the concrete material within the opening as an operating support by the aid of which to form another pocket in the wall of said opening at a level above the first pocket, placing a second quantity of concrete material within said opening to fill the second pocket and to further fill the opening and thereafter continuing in accordance with the number of arms desired.
6. A concrete pile comprising a body of concrete material in pile formation, a plurality of pairs of arms of the concrete material projecting laterally from said body, the arms of each pair being disposed to project from substantially diametrically opposite sides of the body, and a plurality of separately formed reinforcing elements one for each pair of arms, said reinforcing elements extending transversely thru the body and projecting from opposite sides thereof into reinforcing relation with the respective arms.
7. The herein described method of forming within the earth a concrete pile having a reinforced laterally extending integral concrete arm thereon which method consists of forming a pile-shaped opening within the earth, introducing a former into said opening, operating said former to form a pocket within the earth in the wall of said opening, said operation leaving said former extending between said opening and said pocket, and then filling said opening and said pocket with concrete material while said former remains to constitute reinforcing means for the arms.
- In testimony whereof I affix my signature in the presence of two witnesses.
- MAURICE BLUMENTHAL.
